[57] CLAIM

The ornamental design for a crib footboard, as shown and described.

DESCRIPTION

FIG. 1 is a front view of the crib footboard of the present invention;

FIG. 2 is a side view thereof;

FIG. 3 is a top view thereof; and

FIG. 4 is a sectional view taken along line 4—4 of FIG. 1;

FIG. 5 is a sectional view taken along line 5—5 of FIG. 1; and

FIG. 6 is a sectional view taken along line 6—6 of FIG. 1.

The rear surface of the footboard is conventional in appearance.
